UNITED STATES PATENT OFFICE.

HANS OLOF LINDGREN, OF STOCKHOLM, SWEDEN, ASSIGNOR, BY MESNE ASSIGNMENTS, TO THE DE LAVAL SEPARATOR COMPANY, OF NEW YORK, N. Y., A CORPORATION OF NEW JERSEY.

APPARATUS FOR CLEANING THE BOWLS OF CENTRIFUGAL SEPARATORS.

Application filed May 24, 1922, Serial No. 563,408, and in Germany June 17, 1921.

If a liquid containing solid particles of higher specific weight than that of the surrounding liquid be fed through the bowl of a centrifugal separator, a greater or 5 smaller quantity of such particles is separated and will adhere to the inner wall of the bowl. Should so large a quantity be separated that the annular space between the outer periphery of the liner and the 10 inner wall of the bowl be filled the separating operation is to be interrupted for removal of the slime. For the same reason also bowls of centrifugal separators having no liner have to be set out of operation from 15 time to time.

The method commonly used at present consists in that the bowl, if necessary, is taken to pieces and the main part of the slime removed by means of a scraper, whereupon the remainder thereof is removed by 20 the aid of a brush or water, said operation being a time wasting and unpleasant task. Moreover the durability of the bowl is considerably reduced, since the protecting tin 25 coating as well as the soldered parts adapted to maintain the equilibrium are worn away.

This invention relates to an apparatus by means of which the said inconveniences are considerably reduced by the slime being removed by washing. The apparatus consists 30 of a receptacle provided with one or more outlet openings for liquid or steam so arranged that the discharge takes place within the hollow space of the bowl.

According to the nature of the layer of slime different methods may be used. If the quantity of slime is less compressed, it will be sufficient to use water alone or, if necessary, a steam jet. If on the contrary 35 the slime is compressed so as to form a hard mass, it will be necessary first to fill partly with water the receptacle surrounding the slime and then by means of steam or air to set the water into a strong whirling movement so as to loosen and remove the slime.

In order that the same apparatus can be used for all these methods the supply conduit is provided with a controlling device by means of which the supply of water and steam can be controlled, as desired, in various proportions.

In the accompanying drawing three embodiments of the apparatus are illustrated.

Fig. 1 shows one embodiment of the invention in longitudinal section.

Fig. 2 represents a modified form thereof, likewise in longitudinal section, and

Fig. 3 is a sectional view of a further modification.

With particular reference to the drawings, a support A, A¹ or A² respectively for the part of the bowl to be cleaned and a discharging apparatus B, B¹ or B² placed within the hollow space of said part of the bowl are common to all the said embodiments. In Fig. 1 the pipe coil B provided with outlet openings is wound around the tubular support. In Fig. 2 the washing means is introduced in a hollow annular receptacle B¹ supporting the part to be cleaned and the outer wall of which is provided with outlet openings. In Fig. 3 the liquid discharges through a pipe B² parallel with the axis of the bowl. In order to strengthen the washing effect of the jets 75 the support can be so shaped that the bowl is able to be easily set into rotation, as for instance indicated by K in Fig. 3. In all the embodiments it is of advantage that the discharge takes place as near to the layer 80 of slime as possible. To realize the above method of washing away the layer of slime by means of forcibly moving water a receptacle D, D¹ or D² surrounding the member of the centrifugal apparatus is necessary, 85 said receptacle being provided with a drain cock E, E¹ or E² a device F, F¹ or F² controlling the position of the water level and a pipe G, G¹ or G² conducting away air and uncondensed steam. A member H, H¹ 90 or H² is provided for controlling the quantity of the washing means, said member consisting for instance of two or more valves independent of one another.

What I claim as new and desire to secure 95 by Letters Patent of the United States is:—

1. In an apparatus for washing the bowls of centrifugal machines, a receptacle for the bowl, an annular bowl support extending up within the receptacle and means associated therewith to forcibly discharge washing fluid toward the wall of the receptacle, the bowl being adapted to be supported in inverted position within the receptacle with its circular body portion surrounding and 100 spaced from the water-discharging means.

2. In an apparatus for washing the bowls of centrifugal machines, a receptacle for the bowl, an annular bowl support extending up within the receptacle and means associated therewith to forcibly discharge washing fluid toward the wall of the receptacle, and a washing fluid conduit extending downward and inward and communicating with the washing fluid discharging means, the bowl being adapted to be supported in inverted position within the receptacle with its circular body portion surrounding and spaced from the washing fluid discharging means and providing a space between its circular body portion and the receptacle wall and below its lower edge for the specified extension of said washing fluid conduit.
3. In an apparatus for washing the bowls of centrifugal machines, a receptacle for the bowl, an annular bowl support extending up within the receptacle and means associated therewith to forcibly discharge washing

fluid toward the wall of the receptacle, the bowl being adapted to be supported in inverted position within the receptacle with its circular body portion surrounding and spaced from the water-discharging means, and a gas discharge pipe provided with an inlet at its upper end portion and extending down within the receptacle and so positioned as to extend within the bowl and relatively close to its inner wall when the bowl is supported with the receptacle as specified. 25

4. In an apparatus for washing the bowls of centrifugal machines, means to support the bowl in inverted position with its circular body wall surrounding and spaced from the support, and a washing device comprising a pipe provided with fluid-ejecting outlet openings facing the wall of the bowl to be cleaned, said pipe being coiled about the bowl support. 30

In testimony whereof I affix my signature.
HANS OLOF LINDGREN. 35
